PLACE MAT OR THE LIKE

Rose Katz, New York, N. Y.

Application November 15, 1948, Serial No. 149,636

Term of patent 14 years

(Cl. D92—26)

To all whom it may concern:

Be it known that I, Rose Katz, a citizen of the United States, residing in New York city, in the county of New York and State of New York, have invented a new, original, and ornamental Design for a Place Mat or the like, of which the following is a specification, reference being had to the accompanying drawing, forming part thereof.

Fig. 1 is a plan view of a place mat or the like showing my new design.

Fig. 2 illustrates a segment of the place mat on an enlarged scale.

I claim:

The ornamental design for a place mat or the like, substantially as shown.

ROSE KATZ.
